UNITED STATES PATENT OFFICE.

SARAH T. FISHER, OF SPRINGFIELD, OHIO.

DUST-PAN.

SPECIFICATION forming part of Letters Patent No. 292,213, dated January 22, 1884.

Application filed November 13, 1883. (No model.)

To all whom it may concern:

Be it known that I, SARAH T. FISHER, a citizen of the United States, residing at Springfield, in the county of Clarke and State of Ohio, have invented certain new and useful Improvements in Dust-Pans, of which the following is a specification, reference being had therein to the accompanying drawings.

This invention has relation to improvements in dust-pans; and it consists in the construction and novel arrangement of the same, as will be hereinafter more fully explained, and particularly pointed out in the claim appended.

15 The annexed drawings, to which reference is made, fully illustrate my invention, in which Figure 1 represents a vertical sectional view. Fig. 2 is a plan view; and Fig. 3 is also a plan view, showing the device in blank form.

20 Referring by letter to the accompanying drawings, A designates the dust-pan, which is formed of a single piece of metal and bent into shape to form the letter V. The lower portion, a, is flat and extends forward beyond the mouth of the pan, and the portion b is bent forward to form the top of the same. At the sides of the pan the same has wings c, which have the straight edge d and rearwardly-inclined edge e, which, when bent into

a vertical position, form sides to the pan, and on each side of the base of the same are provided lips f, that are bent downwardly on each side of the pan and secured to the inclined side pieces. About the center of the top of 35 the pan is secured a vertical tube, g, which is designed to receive a long handle, by means of which the pan may be used by the operator without the latter stooping.

It will be observed from the above description that by my construction of the pan the same is formed of a single piece of metal, the base, top, and sides being stamped or struck up at the same time, thus producing an improved article of manufacture.

Having described my invention, what I claim, and desire to secure by Letters Patent, is—

As an improved article of manufacture, the herein-described dust-pan, consisting of base 50 a, top b, sides c, and lips f, the whole adapted to be bent in the form described, and provided with the vertical tube g, to receive a handle, as and for the purpose set forth.

In testimony whereof I affix my signature in 55 presence of two witnesses.

SARAH T. FISHER.
